UNITED STATES PATENT OFFICE

153,734

DESIGN FOR A COMBINED CAKE OF SOAP
AND SPOOL HOLDER

Victor Silson, New York, N. Y.

Application June 5, 1948, Serial No. 146,777

Term of patent 3½ years

(Cl. D73—1)

To all whom it may concern:

Be it known that I, Victor Silson, a citizen of the United States of America, residing in New York, county of New York, and State of New York, have invented a new, original, and ornamental Design for a Combined Cake of Soap and Spool Holder, of which the following is a specification, reference being had to the accompanying drawing, forming part thereof.

Fig. 1 is a top plan view of a combined cake of soap and spool holder, showing my new design.

Fig. 2 is a top plan view with the spool holder removed.

Fig. 3 is a side perspective view thereof.

Fig. 4 is a front perspective view of the spool holder.

The opposite side of Fig. 1, presents substantially the same appearance as that shown in the drawing.

I claim:

The ornamental design for a combined cake of soap and spool holder, substantially as shown and described.

VICTOR SILSON.
